UNITED STATES PATENT OFFICE.

OSCAR J. CARLSON, ARVID FRANSEN, AND JOHN FRANSEN, OF CHICAGO, ILLINOIS.

RAIL-SPIKE RETAINER.

Application filed July 12, 1922. Serial No. 574,422.

To all whom it may concern:

Be it known that we, OSCAR J. CARLSON, ARVID FRANSEN, and JOHN FRANSEN, citizens of the United States, residing at 5 Chicago, in the county of Cook and State of Illinois, have invented new and useful Improvements in Rail-Spike Retainers, of which the following is a specification.

This invention relates to a rail spike retainer and has for its primary object the construction of a retainer that will positively prevent accidental removal of the spike.

An object of the invention is the construction and association of parts whereby a spike 15 will be held against loosening and besides materially reinforced against breakage.

Another object of the invention is the novel manner of mounting a clamp and associating the same with the spike so that the 20 spike may be manually removed with very little effort when occasion arises.

A feature of our invention is the novel manner of locking the clamp in place.

With these and other objects of the invention in view the same will be better understood from the following detailed description taken in connection with the accompanying drawing wherein:

Fig. 1 is a top plan view of the retainer in 30 applied position.

Fig. 2 is an end elevation.

Fig. 3 is an enlarged sectional view.

Fig. 4 is a sectional view adjacent the tongue.

Fig. 5 is a sectional view of a modified form of the invention.

Again referring to the drawing and more particularly to Figures 1 to 4 inclusive the numeral 1 designates a plate arranged under 40 the rail 2 and provided with a retaining bead 3. In the manufacture of the plate an opening 4, and hole 5, and groove 6 are formed in the plate. The spike 7 may be of the well known construction consisting of a shank 45 portion 8 and head 9 but for the purpose of bringing about a more effective grip we have shown the spike provided with a projection 10. The clamp 11 consists of a body portion 12 and a dovetail rib 13 that is slid-

50 ably mounted in the groove 6 which is of a corresponding shape. The clamp is provided with a recess 14 for receiving the projection 10 and further has an extension 15 that engages directly over the head of the 55 spike.

As far as we have proceeded it will be

seen that the clamp may be easily forced into position for clamping the spike in place and for preventing accidental removal of the clamp we provide a tongue 16 that has extending therefrom the pin 17 arranged to enter the hole 5 when the tongue is struck a blow and bent as shown in dotted lines. The tongue 16 projects transversely from the end of the body 12 remote from the extension 15 and normally rests in a horizontal position as shown in solid lines in Figs. 2 and 4 of the drawings, but when bent forwardly as shown in dotted lines in these figures the pin 17 enters the hole 5 and locks the clamp 11 70 against accidental movement.

In Figure 5 we have illustrated the clamp 18 as having only the recess 19 thereby dispensing with the extension 15.

It is of course to be understood that the 75 invention may be constructed in various other ways and the parts associated in different relations and, therefore, we do not desire to be limited in any manner except as set forth in the claims hereunto appended. 80

Having thus described our invention what we claim is:

1. In a rail spike retainer, a plate provided with a spike receiving opening and a hole, a clamp slidably carried by said plate 85 and adapted to engage a spike extending through said opening, a tongue formed on said clamp, and a pin on said tongue adapted to engage in said hole.

2. In a rail spike retainer, a plate having 90 an opening and a hole therein, a spike having its shank passed through said opening, a projection on said spike, a clamp carried by said plate, an extension on said clamp to engage over said projection and over the head 95 of the spike, a tongue formed on said clamp, and a pin on said tongue adapted to engage in said hole.

3. A rail spike retainer comprising a plate having a spike receiving opening and a dovetail groove extending to one side of the opening, a clamp having a dovetail shaped rib slidably mounted in the groove, and further having an extension to engage over the spike head. 100

4. In combination a plate having an opening and a groove, a spike adapted to have its shank passed through the opening and provided with a projection, a clamp slidably mounted in the groove and adapted to engage over said projection and over the head 110 of the spike. 105

5. In combination a plate having an opening and a groove, a spike adapted to have its shank passed through the opening and provided with a projection, and a clamp slidably mounted in the groove and adapted to engage over said projection and over the head of the spike, and a tongue formed on the clamp and adapted to be driven into the hole in the plate.
- 10 6. In combination a plate having an opening, a groove, and a hole, a spike adapted to have its shank passed through said opening, a projection on the spike, a clamp having a

rib slidably mounted in the groove, and a recess receiving said projection, an extension 15 on the clamp for engagement over the head of the spike, a tongue extending from the clamp, and a pin on the tongue adapted to be forced into said hole when the tongue is bent.

20 In testimony whereof we affix our signatures.

OSCAR J. CARLSON.
ARVID FRANSEN.
JOHN FRANSEN.
